UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A CORNER-PIECE FOR METALLIC CEILINGS.

SPECIFICATION forming part of Design No. 23,052, dated February 6, 1894.

Application filed January 8, 1894. Serial No. 496,198. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for a Corner-Piece for Metallic Molding, of which the following is a specification, reference being had to the accompanying drawing, forming part hereof, 5 which shows a corner-piece for metallic molding designed according to my invention.

My design consists of a corner piece for a metallic molding ornamented as follows. In general outline the corner piece A is rectangular, and near each of its edges there is a rib or ridge a , in which are arranged, at equal distances apart concaved, circular projections a' . Ribs or ridges a^2 extend from two of the ribs or ridges a , toward the center of the corner piece. The central figure B, is arranged at the corner of the raised molding C, which extends upwardly in an inclined plane from two of the edges of the plate. This molding is ornamented in each of the three sections 15 included between the ribs a and a^2 , as follows. The central section has a triangular projection D, on opposite sides of which are arranged a series of curved ribs d , which join each other at their outer ends in curved lines, 20 the curved rib d' having an oval concave d^2 within it. The other two sections are similarly ornamented. That is, each of them has a triangular projection D, surrounded by curved ribs d , which join each other by curved 25 lines at their outer ends. The central figure B, consists of a concaved, circular projection b , from which radiate a series of pear-shaped projections b' , between which are arranged a series of projections or bars b^2 , having knobs b^3 on their outer ends. This central figure is

surrounded by a series of pyramidal projections E, forming a rectangular figure, two sides of the rectangular figure being arranged close to the edge of the molding. From the two other sides radiate a series of curved ribs 45 F, which extend to the rib or ridge a , at the edge of the plate. Within the curved ribs F is a smaller curved rib f , from which radiate a series of depressions f' . A curved rib or projection G, at the corner of the plate connects with a downwardly inclined curved portion G' , and these portions are ornamented by a central, triangular projection g , around which are arranged a series of inclined ribs g' , which join each other in curved lines at 50 their outer ends. Between the inner edge of the curved projection G, and the edges of the ribs F, are arranged two triangular projections H, and a bird-shaped projection I.

The essential feature of my design is a corner-piece for metallic molding having the center piece formed by a central concaved, circular projection from which radiate pear-shaped projections separated by ribs or bars, and which are surrounded by a series of 65 pyramidal projections from which extend curved ribs, said central portion being bounded by molding divided by ribs into sections and ornamented each with a triangular projection surrounded by curved ribs. 70

I claim—

The design for a corner-piece for metallic molding, herein shown and described.

In testimony whereof I have hereunto subscribed my name.

WILLIAM S. GRAFTON.
